United States Patent Office

Des. 183,517

Patented Sept. 16, 1958

183,517

TIME PUNCH

William H. Harkins, Vestal, Jack W. Stringer, Johnson City, and Walter Furlani, Endicott, N. Y., assignors to International Business Machines Corporation, New York, N. Y., a corporation of New York

Application February 10, 1958, Serial No. 49,566

Term of patent 14 years

(Cl. D64—11)

FIG. 1

FIG. 2.

FIG. 3.

FIG. 4.

Fig. 1 is a front perspective view of a time punch showing our new design.

Fig. 2 is a top view of the same.

Fig. 3 is a side elevational view, the opposite side being substantially similar in appearance; and Fig. 4 is a front view thereof.

We claim:

The ornamental design for a time punch, as shown and described.
